UNITED STATES PATENT OFFICE.

DENNIS J. MCNERNEY, OF PORTLAND, OREGON.

FURNACE.

Application filed March 22, 1921. Serial No. 454,345.

To all whom it may concern:

Be it known that I, DENNIS J. MCNERNEY, a citizen of the United States, residing at Portland, in the county of Multnomah and State of Oregon, have invented new and useful Improvements in Furnaces; of which the following is a specification:

This invention relates to furnaces designed to burn gas, coal or wood, and to give maximum heat with the consumption of a minimum of fuel.

An important object of the invention is the provision of a plurality of units including heating tubes, the units being so disposed with relation to the fire box that they are heated by the products of combustion so as to intensify the heat of the air admitted to the furnace, and to insure the obtaining of the maximum heat with low fuel consumption.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a vertical sectional view through the device, parts being shown in elevation.

Figure 2 is a sectional view on the line 2-2 of Figure 1, and

Figure 3 is a sectional view on the line 3-3 of Figure 2.

Referring to the drawings in detail, A indicates generally the furnace including front and rear walls 10 and 11 respectively which are connected by the side walls 12, the floor line being indicated at 13.

Arranged within the furnace is the fire box indicated generally at B and which comprises a relatively small casing having an open top. The front wall of this casing or fire box is provided with spaced openings 17 and 18 respectively arranged in registration with openings closed respectively by an ash door 19 and a fuel door 20 in the front wall of the furnace proper. The fire box is equipped with fire bricks 21 which are arranged upright and laid edge wise to provide for durability of the fire box. A grate 22 is arranged within the fire box in the

usual well known manner. Secured to the opposed sides of the fire box and on the inclined upper edges thereof are angle irons or the like 23 for supporting the heating drums or units to be presently described.

These heating drums or units are of identical construction, each comprising a casing 24 which is closed at both ends, except for the openings which receive the extremities 25 of the heating tubes 25 which are arranged within the the casing or heating drums in parallelism with each other as clearly illustrated. These tubes are indicated at 25 and may vary in number in accordance with the size of the drum or unit. As shown, the open top of the fire box is closed by two of these units 24 which are arranged at an opposite angle or inclination to each other and supported by the inclined edges of the fire box upon the angle irons above referred to. Interposed between the lower edges of each unit and the angle irons is asbestos packing to provide for a fluid tight joint between these parts. The back and sides of the furnace are formed of inner and outer walls 50 and 51 respectively which define between them a passage 26 for the inlet of cold air from the room above that in which the furnace is located. The lower end of the inner wall 50 terminates above the base or foundation for the furnace so as to permit this cold air to pass to the furnace. The floor 13 is supposed to indicate the floor of the room above that in which the furnace is located and as is customary the opening would naturally be covered with a register which is not illustrated in the drawings as being so common and well known.

The outlet portion 11 of the furnace leads to the center of this register opening while the passages 26 defined by the outer and inner walls extend to the outer portion of the register opening so that hot air from the furnace will enter the room through the portion 11 while cold air within the room will pass down through the passage 26 to the furnace.

Positioned between the fire box and the rear wall of the furnace, is another heating unit indicated at 27 and substantially of the same construction as the heating unit above described, comprising a casing which is closed at both ends except for the openings which receive the heating tubes 28 arranged in parallelism within the drum. This drum or unit is however provided with

a nipple 29 which enters an opening 30 in the adjacent wall of the fire box, to establish communication between the latter and the heating unit or drum 27. The wall of 5 the heating unit opposed to the wall carrying the nipple, is also provided with three openings 30^a and 30^b, preferably arranged in triangular relation. Leading from the uppermost opening 30^a projects a smoke 10 pipe 31 provided with a damper 32. Leading from the other tube openings 30^b of the set of three above referred to, are branch smoke pipes 34 which are connected with the main smoke pipe 31 by branch pipes 35. 15 In practice, when the fire is started within the fire box, the damper is opened so that the products of combustion pass directly from the fire box through the main smoke pipe, a portion of the products of combustion being however utilized to heat the units 20 or drums 24. When desired, the damper in the main smoke pipe may be closed, so that the products of combustion entering the casing of the heating drum or unit 26 is retained therein an appreciable length of time 25 while it finds its way to the branch smoke pipes 34, passing through the latter in the branch pipes 35 and thence to the main smoke pipe at the opposite side of the 30 damper. In this manner, the tubes of the latter mentioned drum or unit are heated to a very high degree, as also the units or drums 24 so that the cold air admitted to the furnace through the air ducts is caused 35 to pass through the tubes of all the unit thereby to be intensely heated. The construction of the furnace in its entirety is very simple, while a compactness and arrangement of the various parts is such that 40 a comparatively smaller furnace may be produced to afford approximately three times the heating surface per square foot of the grate area or surface, thus affording a maximum of heat with the consumption 45 of a minimum of fuel.

While it is believed that from the foregoing description the nature and advantages of the invention will be readily apparent, I desire to have it understood that I do not 50 limit myself to what is herein shown and described, and that such changes may be resorted to when desired as fall within the scope of what is claimed.

What I claim is:—

55 1. A furnace comprising an outer casing,

a fire box including a relatively small casing having an open top, a plurality of heating drums or units closing said top, an additional heating drum or unit arranged at the rear of the fire box and communicating therewith, cold air ducts arranged within the outer casing, a smoke pipe leading from the additional heating drum, and a damper in said pipe.

2. A furnace comprising an outer casing, 65 a fire box including a relatively small casing having an open top, a plurality of heating drums or units closing said top, an additional heating drum or unit arranged at the rear of the fire box and communicating 70 therewith, a smoke pipe leading from the latter mentioned drum or unit, a damper in said pipe, and a plurality of branch smoke pipes leading from the latter mentioned unit and communicating with the main smoke 75 pipe from the rear of said damper.

3. A furnace comprising an outer casing, a fire box including a relatively small casing having an open top, a plurality of heating drums or units closing said top, and 80 angularly disposed relatively to each other, and additional heating drum or unit arranged at the rear of the fire box and communicating therewith, each of said drums or units comprising a casing and a plurality 85 of spaced tubes opening at the ends of the casing, a smoke pipe leading from the additional heating drum, a damper in said pipe, and a smoke pipe leading from said drum and communicating with the main 90 smoke pipe at the rear of said damper.

4. A furnace comprising an outer casing, a fire box including a relatively small casing having an open top and oppositely inclined 95 upper edges, a plurality of heating drums or units supported upon said inclined edges and closing said top, an additional heating drum arranged at the rear of the fire box and communicating therewith, each of said drums including a casing and spaced 100 parallel tubes opening at the ends of the casing, a smoke pipe leading from the additional heating drum or unit, a damper in said pipe, branch smoke pipes leading from said unit and communicating with the main 105 smoke pipe at the rear of said damper, and a cold air duct arranged within the outer casing and terminating below said units.

In testimony whereof I affix my signature.
DENNIS J. McNERNEY.
